UNITED STATES PATENT OFFICE.

BETTIE BROWN, OF MINERALWELLS, TEXAS.

HEADWEAR.

SPECIFICATION forming part of Letters Patent No. 768,356, dated August 23, 1904.

Application filed March 18, 1904. Serial No. 198,796. (No model.)

To all whom it may concern:

Be it known that I, BETTIE BROWN, a citizen of the United States, residing at Mineralwells, in the county of Palo Pinto and State of Texas, 5 have invented a new and useful Headwear, of which the following is a specification.

This invention relates generally to headwear, and particularly to a novel form of bonnet or hat to be worn by ladies and children. 10 The object of the invention is to present a light, durable, cheap, and highly ornamental form of bonnet or hat, which while having all the appearances of being made from varicolored fabric or fabrics will, in effect, be practically devoid of any textile material in its 15 makeup.

With the above and other objects in view, as will appear as the nature of the invention is better understood, the same consists in the 20 novel construction and combination of parts of a head-covering, as will be hereinafter fully described and claimed.

In the accompanying drawings, forming a 25 part of this specification, and in which like characters of reference indicate corresponding parts, there are illustrated two forms of embodiment of the invention capable of carrying the same into practical operation, it being understood that the elements therein exhibited may be varied or changed as to shape, 30 proportion, and exact manner of assemblage without departing from the spirit thereof.

In the drawings, Figure 1 is a view in perspective of a bonnet of the poke type constructed in accordance with the present invention. Fig. 2 is a vertical longitudinal section therethrough. Fig. 2^a is a sectional detail view, on an enlarged scale, of a portion of the bonnet. Fig. 3 is a perspective view of a hat 40 made in accordance with the present invention. Fig. 4 is an inverted perspective view of the hat. Fig. 5 is a view in longitudinal section therethrough.

In certain portions of the United States the 45 climate is exceedingly dry, rains being of rare occurrence and fogs and dew unknown. The headwear constituting the present invention is peculiarly adaptable for use in such sections, owing to the fact that while though exceedingly cheap of manufacture the beauty of

the article when finished and its light and airy appearance render it exceedingly popular.

Of course while the headwear made of the material hereinafter described may be worn for outdoor purposes it is equally adaptable 55 for indoor purposes and will be found of particular utility by actresses.

The material of which the headwear is constructed has the characteristics of being permeable to air, of being readily yieldable without crackling or being permanently wrinkled, of being stretched without danger of tearing, and when released from strain of having retractile properties which will cause the stretched parts to resume their normal condition. 60 All these properties are present in the so-called "crêpe" tissue-paper, and it is from this material that the headwear of this invention will generally be made, although, if preferred, tissue-paper in any other form other 65 than in plain sheets—that is to say, folded or plaited to impart the stretching qualities thereto—may be employed and still be within the scope of the invention.

As herein shown the invention is applied to 75 the manufacture of an ordinary child's bonnet of the poke style and to a lady's hat of the flat low crown style at present in vogue, these two forms of headwear being selected to exhibit two ways of carrying the invention into 80 effect.

In the bonnet shown in Figs. 1 and 2 there is a novel arrangement of ruffles around the front and rear portion of the bonnet, which 85 assist in conveying the impression to a casual observer that the article is made of textile fabric. The crown 1 is made of any suitable material, preferably of stiff paper, covered interiorly and exteriorly by crêpe-paper 2, the 90 crown being of any preferred form that may be desired. Around the front of the crown are arranged two rows of ruffles 3 and 4. The ruffle 3 is disposed adjacent to the outer edge of the crown and projects slightly beyond the 95 same and is secured thereto by rows of stitches 5. The raw or trimmed-off edge 6 of the ruffle is extended beyond the rows of stitches and toward the rear of the crown and operates to hold the ruffle 4 spaced from the ruffle 100

3, thus to give a starched or silky appearance to the bonnet, while the ruffle 4 serves, further, to conceal the edge 6. The ruffle 4 is secured to the crown by rows of stitches 7, and these 5 rows are disposed intermediate of the width of the ruffle 4 to form a rearward-projecting ruffle 8, which lies close to the crown and serves to present an ornamental border to offset and enhance the beauty of the rows of 10 ruffles 3 and 4. The lower portion of the ruffle 3 terminates at or near the lower ends of the sides of the crown; but the ruffle 4 is turned rearward and extends along the bottom edge of the crown and forms side ruffles 9 and 15 bottom ruffles 10, which extend practically to the rear edge of the crown, and these latter ruffles serve to hide the point of attachment to the crown of a cape 11, which is also ruffled, and extends entirely around the sides of 20 the crown and the rear portion of the bonnet. Extending around or approximately around the entire portion of the crown is a ruffle 12, which projects toward the ruffle 8, the ruffle 12 being secured in place by a full peak 13, 25 which is shaped to cause an artistic finish to the rear of the bonnet. The ruffle 12 and peak are secured to the crown by rows of stitches 14, the raw or trimmed-off edges 12' and 13' of the ruffle and peak, respectively, 30 being disposed within and thus concealed by the peak. The lower portion of the peak and the cape are gathered and adjusted through the medium of side strings 15, which are tied in a bow-knot at the rear, and serve to conceal 35 the point of juncture between the lower end of the peak and the upper end of the cape. By the peculiar manner of attaching the ruffles and peak to the crown all rough edges are effectually concealed, with the result that 40 a neat and highly-finished article is produced.

In the form of embodiment of the invention shown in Figs. 3, 4, and 5 the brim 16 is made of stiff paper or pasteboard and is covered by crêpe-paper 17 on both sides. 45 The rear portion of the brim is provided with an opening, as usual, to accommodate the hair of the wearer, and surrounding this opening and secured thereto in any suitable manner is a bandeau 18, the outer face of which is ornamented by varicolored plaited cords of paper 19, it being obvious, however, that the bandeau may be ornamented in any other manner that may be desired. The bandeau is preferably covered by textile fabric 20 and has 50 an upper lining 21 of the same material, although this is not essential. The upper portion of the brim at its front and surrounding its rim is ornamented in any suitable manner, as by braided strips 22 of varicolored 55 paper or by the employment of any other suitable ornamentation at this point, the said ornamentation serving to shield from view the lines of stitches 22' that hold the covering 17 in place and also to hide the raw or 60 trimmed-off edge 23 of the covering. Sur-

rounding the bandeau-opening is a full peak or crown 23', and disposed in advance of the front portion of the peak and projecting nearly to the rim ornamentation is a ruching 24, the attaching-stitches 25 of which are concealed by the bunched forward portion of the peak. As in the form of embodiment of the invention shown in Figs. 1 and 2 the raw or trimmed-off edges 26 and 27 of the peak and covering are disposed within the peak and are 75 thus shielded from view.

By the mode of procedure adopted in the manufacture of headwear under this improvement all seams and stitches are concealed and the finished article has all the appearances of 80 one made of textile material such as commonly employed.

The paper employed in the manufacture of the bonnet or hat may have its edges dipped in any suitable coloring-matter to give a fringe 85 effect to the exposed portions of the covering and other parts of the headwear, and this, together with any other ornamentation that may be adopted, will give a highly-finished and artistic appearance to the article. 90

Having thus fully described my invention, what I claim is—

1. A head-covering comprising a crown, a cover therefor, a row of ruffles disposed near the outer edge of the crown and having its raw or trimmed-off edge disposed toward the rear of the crown, a second row of ruffles secured to the crown and held spaced from the first-named row by the trimmed-off edge, a row of ruffles surrounding the rear portion 100 of the crown, and a peak secured to the crown by rows of stitches passing through the last-named ruffle, the trimmed-off edges of the last-named ruffle and peak being disposed within the latter. 105

2. A head-covering comprising a crown, a cover therefor, a row of ruffles secured to the outer edge of the crown and terminating at the lower side thereof, a second row of ruffles secured intermediate of their width to the crown and presenting upstanding and approximately horizontal portions, a third row of approximately horizontally-disposed ruffles arranged near the rear of the crown, a peak held assembled with the crown by rows of stitches 115 passing through the third row of ruffles and the crown within the peak, and a cape secured to the lower side of the crown and having its point of attachment therewith concealed by side extensions of the second row of ruffles. 120

3. A head-covering comprising a crown, a cover therefor, a row of ruffles secured to the outer edge of the crown and terminating at the lower side thereof, a second row of ruffles secured intermediate of their width to the 125 crown and presenting upstanding and approximately horizontal portions, a third row of approximately horizontally-disposed ruffles arranged near the rear of the crown, a peak held assembled with the crown by rows of stitches 130

passing through the third row of ruffles and the crown within the peak, a cape secured to the lower side of the crown and having its point of attachment therewith concealed by 5 side extensions of the second row of ruffles, and gathering-strings secured at the rear of the crown and serving to conceal the point of juncture of the cape with the peak.

4. A head-covering comprising a crown, a 10 cover therefor, a row of ruffles secured to the outer edge of the crown and terminating at the lower side thereof, a second row of ruffles secured intermediate of their width to the crown and presenting an upstanding and a 15 rearwardly-extending approximately horizontal portion, the lower ends of the second row of ruffles being extended along the bottom of the crown and forming side extensions, a third row of approximately horizontally-

disposed ruffles arranged near the rear of the 20 crown and projecting forward, a peak held assembled with the crown by rows of stitches passing through the third row of ruffles and the crown within the peak, a cape secured to the lower side of the crown and having its 25 point of attachment therewith concealed by the side extensions of the second row of ruffles, and gathering-strings at the rear of the crown and serving to conceal the point of juncture of the cape with the peak.

In testimony that I claim the foregoing as my own I have hereto affixed my signature in the presence of two witnesses.

BETTIE BROWN.
